TIE FORMING AND HOLDING PIN

Walter R. Rees, Kansas City, Mo.

Application July 25, 1949, Serial No. 106,554

3 Claims. (Cl. 2—157)

1

This invention relates to accessories for use with clothing and more particularly to a pin adapted for releasable mounting on a necktie in such manner as to hold the tie in a desired, attractive manner extended outwardly from the wearer's body in a slight bulging, the pin also being adapted to maintain the tie with its knot properly aligned in place.

It is the most important object of the present invention to provide a forming and holding pin for neckties having a pair of spaced apart clips, each adapted for releasable connection with the tie behind one length thereof and having a member joined therewith by resilient means for engaging the tie and not only holding the same slightly protruded but transversely taut.

Other objects of the present invention relate to the way in which the necktie pin is provided with a pair of spaced apart clips that are held biased apart by resilient arms, the arms being integral and formed into a loop, which loop serves as a means to hold the tie in a bulged condition; the way in which the loop and the clips are normally in spaced apart parallel planes; the way in which the distance between the aforesaid planes increases as the clips are moved together; and the manner of limiting the extent of resiliency in the tie-engaging loop itself.

Other more minor objects will be made clear or become apparent as the following specification progresses, reference being made to the accompanying drawing, wherein:

Fig. 1 is a side elevational view of a necktie showing the position and form thereof when the pin forming the subject matter hereof is placed in use.

Fig. 2 is a front elevational view of the tie showing the position of the forming and holding pin made in accordance with my present invention.

Fig. 3 is a front elevational view of the pin per se.

Fig. 4 is a rear elevational view thereof.

Fig. 5 is a top plan view of the pin showing in dotted lines the position of the component parts thereof when the pin is in use; and

Fig. 6 is a transverse, cross-sectional view taken on line VI—VI of Fig. 4.

Wearers of neckties appreciate the aggravating problem of maintaining the knot of the tie in the desired position and against loosening as well as the problem of holding the tie in an attractive position slightly bulged outwardly away from the shirt adjacent the knot.

Many attempts have heretofore been made to

2

provide pins and the like to meet these problems but for the most part the same have been complicated, heavy, inexpensive and unattractive. As will hereinafter appear, the pin forming the subject matter hereof is simple, easy to apply and remove, capable of holding the tie exactly as desired and of such nature as to be completely hidden from view when mounted upon the tie and placed in use.

10 The pin forming the subject matter hereof is adequately set forth in Figs. 3 to 6 inclusive as well as in Fig. 2 by dotted lines behind one length 10 of a necktie broadly designated by the numeral 12. As is well known, the tie is formed into a knot 14 after encircling the neck of the wearer beneath collar 16 of a shirt. The stretch or length 10 thereof which covers and hides from view the shorter stretch 17 of the tie is relatively wide and should be kept stretched to its full width as nearly as possible for attractiveness.

Furthermore, it is desirable that the knot 14 and the tie 12, take the form shown in Fig. 1 where the knot 14 thereof is drawn taut and where the downwardly depending stretches 10 and 17 of the tie 12 are held away from the front of the wearer's shirt.

For the most part, the pin is formed from an initially straight length of material that may be wire-like and that is resilient. Such elongated length of wire-like material is first formed midway between the ends thereof into a loop 18 presenting a pair of legs 20 and 22 that cross and engage at 24. The outermost ends of the legs 20 and 22 are thereupon formed into clips of identical nature, both of which are designated by the numeral 28.

Clips 28 are preferably formed into a circle and terminate in a cross pin 30 that extends diametrically across the loop. The free end of the pin 30 is sharpened as at 32. That end of the pin 30 opposite to its sharpened point 32 is secured directly to the respective leg 20 or 22 as the case may be as by soldering 34. It is noted that the pins 30 converge as the soldered ends 34 thereof are approached, extend through the loop forming the clips 28 and are held in engaging relationship with the loop adjacent the end 32 thereof by the inherent resiliency of the material from which the entire pin is formed.

50 The legs 20 and 22 are not interconnected at the crossing point 24 but are in slidably interengagement and are held in such position by the resiliency of the material from which the pin is made.

55 The loop 18 is held against undue flexing

movement by a transverse strap 36 having ears 38 on the ends thereof that overlap and clip tightly upon the loop 18 for holding strap 36 in place.

As shown in full lines in Fig. 5, the two loops forming clips 28 are normally in a plane that is spaced from and substantially parallel with the loop 18. Because of the resiliency of the arms 20 and 22, the clips 28 will move toward and away from the plane of the loop 18 as shown by dotted lines in Fig. 5 and furthermore, the clips 28 may move toward and away from each other. Obviously, as the arms 20 and 22 are moved to increase the size of the loop by moving the clips 28 toward each other, the loop 18 will be moved outwardly with the distance between the planes of the loops 18 and the clips 28 increased.

In use, the pin is placed behind the stretch 10 of tie 12 slightly below the knot 14 thereof with that face of the pin shown in Fig. 4 next adjacent the wearer's shirt. Before applying the clips 28 to the tie 12, the operator moves clips 28 slightly together as shown by dotted lines in Fig. 5 and forces the pins 32 into the fabric material from which stretch 10 of tie 12 is made. Because of the double thickness of the stretch 10 at the point of application of the device, the pins 32 will pierce the rearmost thickness of stretch 10 and not protrude through to the outermost face of the tie 12. Furthermore, because of the way in which the pins 32 bear against their respective loops, the fabric of the tie 12 will be clamped tightly in place and yet permit easy removal of the device from the tie. After the two clips 28 have been applied to the tie 12, the tendency for the same to move outwardly away from each other because of the resiliency of loop 18, will cause the stretch 10 of the tie 12 to be held taut transversely. Furthermore, the tendency of the clips 28 to move away from each other, will cause the loop 18 to be held outwardly in an offset relationship with respect to the clips 28 and thereby hold the tie 12 bulged slightly outwardly immediately below the knot 14 as at 40. The tie 10 will accordingly, as shown in Fig. 1, be transversely arched at the bulge 40 and when viewed from the side, the entire device forming the subject matter hereof, will be fully hidden from view. When the tie is held in a bulged condition, as well as transversely taut, immediately below the knot 14, the latter will not have a tendency to become loose and misplaced. Instead, knot 14 will assume an angular position as shown in Fig. 1, will not slide beneath the collar 16, and will not hang downwardly in a loose condition as is common when a device of the nature hereof is not used.

The unattractive flat condition of the tie against the chest of wearer is entirely eliminated. Furthermore, the holding pin is easily applied and removed and will not become displaced because of the way in which the pins 32 cooperate with their respective loops in gripping the fabric material from which the tie is made.

It is also to be noted that the clips 28 formed as shown and described, will not harm the material from which the tie is made irrespective of the number of times the pin is applied and removed to the tie 12 because solder 34 limits the extent of movement of the fabric onto pins 30.

By use of the strap 36 flexing movement of the loop 18 is limited to points adjacent the crossing point 24 of legs 20 and 22 and loop 18 is therefore, rendered more rigid and capable of 70

holding the tie transversely taut without undue stretching or harmful effects thereon.

The angularity of the pins 30 serves to hold the device in place since there is always a tendency for the pins 30 to move into the fabric by the action of arms 20 and 22.

It is also to be noted that the back stretch 17 of the tie 12 is inserted between the stretch 10 and the loop 18. Thus, the two stretches 10 10 and 17 do not become relatively displaced from the desired superimposed relationship. Further, the two stretches 10 and 17 are free to slip longitudinally, and binding, that takes place when such stretches are pinned together or to the 15 wearer's shirt, is eliminated.

It is appreciated that many changes and modifications may be made to the tie holding and forming pin forming the subject matter hereof and those that fairly fall within the broad concepts of the invention as defined by the appended claims, are contemplated hereby.

Having thus described the invention, what is claimed as new and desired to be secured by Letters Patent is:

25. 1. A support for neckties comprising an elongated member of resilient material, rebent intermediate the ends thereof to present a loop having an arcuate bight at the normally lowermost end thereof and a pair of integral arms at the normally uppermost end thereof, said arms extending upwardly and outwardly away from said uppermost end of the loop and diverging relatively as the outermost ends thereof are approached; and a tie-engaging element on each arm respectively at 30 said outermost end thereof remote from the loop, said elements being in a common plane and said loop being in a second plane spaced from the plane of said elements, said arms being crossed adjacent said uppermost end of the loop for sliding interengagement, whereby as the elements are moved toward each other to increase the size of the loop, the distance between the plane of the elements and the plane of the loop is increased.

2. A support for neckties comprising an elongated member of resilient material, rebent intermediate the ends thereof to present a loop having an arcuate bight at the normally lowermost end thereof and a pair of integral arms at the normally uppermost end thereof, said arms extending upwardly and outwardly away from said uppermost end of the loop and diverging relatively as the outermost ends thereof are approached; a tie-engaging element on each arm respectively at 45 said outermost end thereof remote from the loop, said elements being in a common plane and said loop being in a second plane spaced from the plane of said elements, said arms being crossed adjacent said uppermost end of the loop for sliding interengagement, whereby as the elements are removed toward each other to increase the size of the loop, the distance between the plane of the elements and the plane of the loop is increased; and an elongated, stabilizer plate extending diametrically across said loop between said bight and the arms, both ends of the plate being secured to the loop and the longitudinal axis of the plate being parallel with a line joining said elements.

3. A support for neckties as set forth in claim 1 wherein each of said elements includes a single annulus having a pair of ends, the corresponding arm being integral with one end of the annulus and extending tangentially outwardly away therefrom; and an integral, elongated pin on the opposite end of the annulus and extending diametrically through the annulus, terminating in a

pointed end projecting beyond the annulus, the opposite end of the pin being joined to the proximal arm on one side of the annulus closing the latter, and said pin engaging the annulus on the opposite side of the latter intermediate the ends of the pin.
